POWER ACTUATOR.

Original application filed June 26, 1924, Serial No. 722,487. Divided and this application filed January 31, 1925. Serial No. 5,948.

Our invention consists in the novel features hereinafter described, reference being had to the accompanying drawings which illustrate several embodiments of the same, selected by us for purposes of illustration, and the said invention is fully disclosed in the following description and claims.

This application is a division of our former application filed June 26, 1924, and given Serial No. 722,487.

In carrying out our invention we employ a power actuator especially adapted for use in brake mechanisms for automobiles and particularly with automobiles provided with brakes on all four of the supporting wheels, the actuator being provided with two pistons working in the same cylinder, each of which pistons is operatively connected with the brake mechanism for two wheels, preferably arranged opposite to each other at the same end of the chassis. The pistons are caused to move in the cylinder toward and from each other by establishing differential pressures between that portion of the cylinder between the pistons and the portions at each end of the cylinder on the opposite sides of the piston, and we provide reversing valve mechanism connected with an operator operated device for controlling the movements of said pistons, the valve mechanism being constructed to maintain the pistons in balanced condition at any interjacent position of the valve mechanism between its limits of movement, so that the movements of the pistons and their connected brake mechanisms can be controlled with the utmost delicacy, while the operator is relieved from the exertion of actually operating the brake mechanism. The valve mechanism is also connected to one of the pistons by means permitting lost motion, so that in case of failure of the power, the said piston and its connected brake mechanism may nevertheless be operated directly by the operator. In the application of our improved mechanism to automobiles in which an internal combustion engine furnishes the propelling power, the internal combustion engine affords a convenient means of obtaining the differential pressures required. Thus, in the operation of an internal combustion engine, there is suction produced by the cyl-

inders in drawing in the charges of explosive mixture, between the cylinders and the throttle valve which is at its maximum when the engine is throttled down, and decreases as the throttle is opened. There is also high compression in the cylinders of the engine which is greatest when the throttle is wide open, and decreases as the throttle is closed. Our improved power actuator, can, therefore, be readily operated by the suction from the intake manifold as the low pressure acting on one face of each piston, and atmospheric air as the high pressure acting on the opposite face of each piston, or by compressed gases from a cylinder of the engine providing the high pressure acting on one face of each piston and atmospheric air as the low pressure acting on the other face of each piston, or compressed gases from a cylinder of the engine may be employed as the high pressure and suction from the intake manifold may be employed as the low pressure. In practice, however, we find it most convenient and advantageous to employ the suction from the intake manifold for the low pressure and atmospheric air for the high pressure, as specifically shown in the accompanying drawings. Our present invention also contemplates means for preventing one of the pistons from movement in the cylinder and thereby holding out of operation the brake mechanism connected therewith, leaving the other piston to operate the brake mechanism connected to it so that in a four wheel brake mechanism for example, the operator operated part, as the foot lever, may be operated under normal conditions so as to apply only two of the brakes, as those for the rear wheels, while in an emergency, or when heavy braking action is required, the locked piston may be released so that both pistons will operate, and simultaneously apply the brakes of all four of the wheels, when required, and under the entire control of the operator. In this instance this is accomplished by providing mechanical means for locking and unlocking the free piston not under the mechanical control of the operator operated part.

Referring to the accompanying drawings, Fig. 1 is a diagrammatic view representing an automobile provided with four brakes,

one for each of the wheels thereof, and having our improved double piston power actuator operatively connected therewith, and with the intake manifold of the engine for supplying the lower pressure for operating the power actuator.

Fig. 2 is an enlarged sectional view of the double piston power actuator.

Fig. 2^a is a detail drawn to an enlarged scale, showing the parts at the left of Fig. 2.

Fig. 2^b is a section on the line 2^b—2^b of Fig. 2^a looking in the direction of the arrow.

Figs. 3 and 4 are enlarged sectional views of a form of valve mechanism which may be conveniently employed in connection with the power actuator, showing the valve mechanism in reversed positions.

Referring to the drawings, 201, represents the power cylinder of our improved power actuator, both ends being closed by suitable heads, indicated at 202—203 respectively, secured to the cylinder by any suitable means, as by connecting bolts and nuts, 204, see Fig. 1. Within the cylinder, 201, is a main double-acting piston, indicated at 210, provided with annular gaskets, 211, extending in opposite directions and engaging the inner surface of the cylinder wall. The piston, 210 is provided with a hollow piston rod, 212, which extends through a guiding sleeve, 213, bushing, 214, and stuffing box, 215, with which the head, 203, of the cylinder is provided. The cylinder is also provided with a second piston, 210^a, which we term the auxiliary or floating piston, having similar gaskets, 211^a, extending in opposite directions, and engaging the inner surface of the cylinder. The piston 210^a, is provided with a hollow piston rod, 212^a, extending through a guiding sleeve, 213^a, bushing, 214^a, and stuffing box, 215^a, with which the head 202, of the cylinder is provided. The opposite ends of the cylinder are connected by means of a pipe, or passage, 270, so that one or both of said pistons may be actuated by creating differential pressures in the space, A¹, between said pistons and the connected spaces, B², B³ at the opposite ends of the cylinder. 216, 216^a represents a longitudinally movable valve sleeve extending in opposite directions from the reversing valve mechanism, which in this instance is located in the hub of the main piston, 210. The piston, 210, is provided with two chambers, indicated respectively at 228 and 230. The chamber, 228, is connected by passages, 239—240 with the central portion, A¹, of the cylinder between the pistons, while the chamber, 230, is connected by passage, 236, with the portion, B², in the end of the cylinder beyond the piston, 210, which, through the pipe, or passage, 270, is connected to the portion, B³. Within the chamber, 228, is a valve collar, 227, secured to the valve sleeve, which is ground to fit the interior of the chamber,

228, and is movable therein between end washers, 227^a and 227^b, of leather or other suitable material, thus establishing a limit of lost motion amounting to substantially $\frac{7}{16}$ of an inch in this particular instance 70 between the valve sleeve and the piston, 210. The portion, 216, of the valve sleeve, also communicates with a plurality of air inlet ports, 225, which can be brought into communication with the chamber, 228, when the valve, 227, is in one extreme position, and can be brought into communication with the chamber, 230, when the valve is in its other extreme position, the said ports, 225, being maintained closed when in an interadjacent 80 position between the limits of movement of the valve mechanism. Within the chamber, 230, the valve mechanism is provided with a collar valve, 229, ground to fit the wall of the chamber and movable within 85 said chamber between end washers, 229^a, and 229^b, and the portion, 216^a of the valve sleeve is provided with a plurality of suction ports, indicated at 224, which are capable of being brought into communication with the chamber, 230, in one extreme movement of the valve mechanism and into communication with the central space, A¹, of the cylinder when in the other extreme position of the valve mechanism, said ports being normally 95 closed when the valve mechanism is in an interadjacent position. For convenience of reference we term the ports, 224, the low pressure ports, and the ports, 225, the high pressure ports. 100

In this instance, as shown in Figs. 1 and 2, the low pressure is supplied by suction from the intake manifold, 221, of the internal combustion engine, 222, of the automobile which is connected to an inlet port, 220, in the exterior portion of the piston rod, 212^a, by a flexible connection permitting the necessary movement of the piston rod. In order to insure the instantaneous operation of the brake mechanism without interference with idling of motor, etc., we prefer to interpose a vacuum tank between the intake manifold and the actuator, and in Fig. 1, we have shown such a tank at 223^a, connected by a pipe 223, with the intake manifold, said pipe being preferably provided with a regulating valve, 223^d, adjacent to the manifold, and a check valve 223^b, adjacent to the tank. A flexible pipe, 223^c, which may be of considerable diameter, extends from the tank, 223^a, to the ports, 220. Communication between the port, 220, and the low pressure ports, 224, is established through the hollow piston rod, 212^a, and the movable valve sleeve section, 216^a. 110

In order to further provide for cutting off the suction when the pistons are in retracted positions, which is the normal or "off" position of the pistons, as indicated in Fig. 2, we prefer to provide the hollow piston rod 130

212^a with a plug or partition 218^a permanently secured therein adjacent to the port 220, and provided with an axial aperture 218^b and a valve seat 218^c as best shown in Fig. 2^a. We also provide a valve 218 for engaging the valve seat 218^c when the parts are in normal or "off" position, said valve being secured to a rod 209, extending through the hollow piston rod, and being connected to the sleeve section 216^a, by means providing lost motion, in this instance a wrist pin 219, on the rod 209, engaging a slot 219^a in the sleeve section. When the pistons move away from each other and return to normal or retracted positions as shown in Fig. 2 the wrist pin 219 will be engaged by the end of slot 219^a, in the sleeve 216^a and this will draw the valve 218 firmly upon its seat and form an additional sealing means when the parts are not in operation. When the valve sleeve 216^a is moved in the direction of the arrow in Fig. 2, the end of slot 219^a relieves the wrist pin 219, and permits the valve 218 to open by suction, and it will be assisted in opening by the frictional engagement between valve sleeve, 216^a, and the wrist pin. The valve 218 will remain open until it is closed by the return of the pistons and valve sleeve 216^a to normal or retracted positions. The slot 219^a permits the valve sleeve to move in the direction of the arrow, Fig. 2, to a greater or less extent as required without interference from the valve rod 209.

35 The higher pressure fluid in this instance is atmospheric air, which is admitted to the interior of the valve sleeve section, 216, through a port or opening, 243, at the outer end of the valve sleeve section, and preferably provided in a plug, 241, screwed into the outer end of the hollow piston rod, 212, and provided with perforated ears, 242, by which it is connected to one pair of brake mechanisms, as the brakes for the rear wheels of the automobile. The outer end of the other piston rod, 212^a, is provided with similar ears, 242^a, by which it is connected to the remaining brake mechanisms, as the brakes for the front wheels. In the present instance as shown in Fig. 1, the piston rod, 212, is connected by a link, 263, with an arm, 264, on a rock shaft, 259, provided with arms, 258, each of which is connected by a link, 257, to an arm, 256, for rotating forwardly a cam, 255, of one of the rear wheel brake mechanisms, which in this instance, is shown as comprising brake drums, 252 and separable braking shoes 253, pivoted at 254, and provided with the usual retracting springs, 261. It is to be understood, further, that the particular form of brake mechanism and its connections with the actuator form no part of our present invention. The piston rod, 212^a, is connected in a similar manner with the brake mechanisms for the

forward wheels and the various parts of the brakes and connecting mechanisms are indicated by similar numerals.

250 represents the operator operated part which in this instance is the usual foot lever pivoted to the chassis and provided with a retracting spring, 251. This lever is connected to the longitudinally movable valve sleeve, 216—216^a, and reversing valve mechanism by any usual or desired means. In the present instance we have shown the lever, 250, connected by a link rod, 262, with a rectangular frame comprising longitudinally movable slide rods, 271, engaging guiding apertures, 272, in parts secured to the cylinder heads and projecting therefrom, said rods being connected at their forward ends by cross rod, 273, extending around the piston rod, 212^a, and being provided at their rear ends with a cross rod, 274, which extends through a slot, 275, in the piston rod 212, and engages suitable apertures in the sleeve, 216, so that the sleeve and valve mechanism, including the collar valves, 227 and 229, may be shifted longitudinally with respect to the piston, 210, by the operation of the foot lever, and in the reverse direction by the retracting spring, 251.

Our invention also contemplates, as before stated the employment of means whereby one of the pistons, as the auxiliary or floating piston, 210^a, may be permitted to remain stationary while the main piston is operated, thereby effecting the operation of one set of brakes, only, and for releasing the said auxiliary or floating piston, to secure the simultaneous operation of the brake mechanisms connected with both pistons when required under the control of the operator. This is particularly advantageous in connection with an automobile having four wheel brakes, as it enables the operator to apply the brakes of two wheels, as the rear wheels, under ordinary working conditions, and also to bring into action the brakes of all four wheels in any emergency, or when it is desired to make a sudden stop, or when additional braking power is required, as on very steep hills. The piston rod, 212^a, connected with the floating piston, is provided in this instance with a groove or recess, 280, adapted to be engaged by a rounded spring detent, 281, mounted in a recess, 282, in the sleeve, 213^a, of the actuator cylinder, 202, and provided with a spring, 283, held in position by a screw plug, 284, screwed into the recess, 282, by means of which the tension of the spring may be adjusted. The engagement of the detent, 281, with the recess, 280, in the piston rod, 212^a, is such that the auxiliary or floating piston, 210^a, will be normally held against movement when the valve mechanism of the actuator is moved into position to connect the central portion of the actuator cylinder with the suction, thus per-

mitting the main piston, 210 connected with the valve sleeve, to be actuated in either direction to apply and release the brakes connected therewith.

5 In the operation of the apparatus, when it is desired to apply only one set of brakes, the operator will depress the foot lever 250, thereby shifting the sleeve 216 and the reversing valve mechanism in the direction of 10 the arrow, Fig. 2, and moving the valves into the position shown in Fig. 3. This releases the sealing valve 218 and permits it to be opened by the suction and brings the 15 low pressure ports 224, into communication with the central space A¹ between the pistons and the high pressure ports 225 into communication with the opposite end portions of the cylinder, thus exhausting air from the 20 central portion A¹ and admitting air to the end portions of the cylinder. As the piston rod 212^a is held in locked position by the 25 detent 281, the floating piston 210^a will remain stationary and the piston 210 will move inwardly and apply the brakes connected therewith. It will be understood that if the 30 pedal 250 is moved forward and held, the movement of the piston will follow until the piston 210 covers the low pressure ports, 35 when it will be held in balanced condition, until a further movement of the valve mechanism under the actuation of the pedal takes place, a further forward movement of the pedal is instantly followed by a movement 40 of the piston and the brake mechanism can be applied with the same accuracy and delicacy as is obtained by the usual foot operated brake.

When the operator releases the pedal 250, 45 it will be moved in the opposite direction by spring 251, thereby shifting the valve sleeve and reversing valve mechanism so as to place the low pressure ports 224, in communication with chamber 230, and the cylinder end portions and the high pressure ports, 50 225, in communication with central space A¹ between the pistons, exhausting air from the end portions of the cylinder and admitting atmospheric air to central space A¹, and moving piston 210 back to normal position and releasing the brakes connected therewith.

In case more than normal braking is required, the piston 210 is actuated until arrested by the application of its connected 55 brake mechanism as before described and a further depression of the brake pedal sufficient to actuate the valve sleeve, 216^a to its full extent will increase the suction within the central space, A¹, in the cylinder between the pistons. When the suction has increased 60 sufficiently to enable the piston, 210^a to overcome the retarding influence of the detent, the latter will yield and be forced downward against its retracting spring, thus per-

mitting the floating piston, 210^a, to move inwardly and apply the brake mechanism connected therewith, as the front wheel brakes. This movement of the floating piston, 210^a, is retarded by the restricted size of the passage, 270, preventing the too sudden application of the brakes connected to piston, 210^a, thereby giving the operator the opportunity of slightly releasing the brakes, if he so desires, before the full effective force of the 70 additional two brakes is reached. This passage may be provided with an adjustable valve, if desired, or the pipe, 270, may be of such size to provide the desired restricting effect. When the reversing valve mechanism is shifted in the opposite direction by the brake pedal under the action of its retracting spring, both pistons will return to their normal positions, and as soon as the auxiliary or floating piston, 210^a, is moved 75 far enough to bring the groove or recess, 280, into engagement with the detent, 281, the latter will spring into place and again lock the auxiliary piston. This construction will, 80 therefore, enable the operator to actuate one 85 of said pistons, and the brake mechanism connected therewith, as the brakes for the rear, wheels or both pistons, and the brakes for all four wheels, as may be required.

It will also be noted that by reason of the lost motion between the piston, 210, and the reversing valve mechanism, that if the brake pedal, 250, is actuated and for any reason the pressure fails, further pressure on the 90 pedal will bring the collar valves, 227, and 95 229, against the ends of the chambers, 228 and 230, automatically venting the cylinder, and the operator can then apply physical pressure to the brake pedal to directly move the piston, 210, thus applying 100 the brakes connected therewith by direct physical force of the operator, and thereby preventing what otherwise might result in an accident. It is also to be noted that in the operation of our improved brake mechanism by means of the herein described 105 power actuator, the operator operates the brake pedal in exactly the same manner as to direction of movement and extent of movement as is usual in installations where 110 the power is applied wholly by the operator so that it is unnecessary for the operator 115 to learn a new mode of operation, while at the same time the brakes may be applied and released by the power actuator without any further exertion on the part of the operator than is required to move the 120 brake pedal and connected valve mechanism against the pressure of the retracting spring.

What we claim and desire to secure by 125 Letters Patent is:—

1. The combination of a power actuator comprising a cylinder closed at both ends, a pair of double acting pistons located in the cylinder, said cylinder being provided with 130

- 4 a communicating passage connecting its end portions, means for establishing differential pressures in the central portion of the cylinder between said pistons and the connected 45
 5 end portions, including reversing valve mechanism, an operator operated part, connections therefrom to the reversing valve mechanism, a piston rod connected with each 50
 10 of said pistons and extending through the end of the cylinder adjacent thereto, independent brake mechanism connected to each 55
 15 of said piston rods, one of said piston rods being provided with a recess, and a spring actuated detent supported in a part connected with the cylinder and provided with a rounded portion engaging the recess in the adjacent piston rod, for normally holding 60
 it and its connected piston from movement with respect to the cylinder. 65
2. The combination of a power actuator comprising a cylinder closed at both ends, a pair of double acting pistons located in the cylinder, said cylinder being provided 70
 20 with a communicating passage connecting its end portions, means for establishing differential pressures in the central portion of the cylinder between said pistons and the connected end portions, including reversing 75
 25 valve mechanism, an operator operated part, connections therefrom to the reversing valve mechanism, a piston rod connected with each 80
 30 of said pistons and extending through the end of the cylinder adjacent thereto, independent brake mechanism connected to each 85
 35 of said piston rods, one of said piston rods being provided with a spring actuated detent for normally holding it and its connected piston from movement with respect to the cylinder. 90
3. The combination of a power actuator comprising a cylinder closed at both ends, a pair of double acting pistons located in the cylinder, said cylinder being provided 95
 40 with a communicating passage connecting its end portions, means for establishing differential pressures in the central portion of the cylinder between said pistons and the connected end portions, including reversing
- valve mechanism, an operator operated part, connections therefrom to the reversing valve mechanism, a piston rod connected with each 45
 50 of said pistons and extending through the end of the cylinder adjacent thereto, independent brake mechanism connected to each 55
 55 of said piston rods, one of said piston rods being provided with a recess, and a spring actuated detent supported in a part connected with the cylinder and provided with a rounded portion engaging the recess in the adjacent piston rod, for normally holding 60
 it and its connected piston from movement with respect to the cylinder. 65
4. The combination of a power actuator comprising a cylinder closed at both ends, a pair of double acting pistons located in the cylinder, said cylinder being provided with a communicating passage connecting its end portions, means for establishing differential pressures in the central portion of the cylinder between said pistons and the connected end portions, including reversing valve mechanism, an operator operated part, connections therefrom to the reversing valve mechanism, a piston rod connected with each 70
 75 of said pistons and extending through the end of the cylinder adjacent thereto, and locking mechanism for locking one of said piston rods and its connected piston with respect to the cylinder to prevent movement thereof, independent brake mechanisms connected respectively to said piston rods, said communicating passage between the end portions of the cylinder being constructed to restrict the passage of air therethrough to prevent the too sudden movement of the piston connected with the lock engaging piston rod when the locking mechanism is released. 80

In testimony whereof we affix our signatures. 85
